UNITED STATES PATENT OFFICE

2,048,346

MEANS FOR SECURING MATERIAL TO
BOARDS AND TABLETSVivian Charles Eric Marten-Gwilliam,
Aldeburgh, EnglandApplication December 13, 1934, Serial No. 757,353
In Great Britain December 14, 1933

4 Claims. (Cl. 45—131)

This invention is devised for the object of effectively attaching, holding or retaining in position, any material such as drawing paper, writing material, or tracing cloth or both on to any existing drawing board, desk or tablet which has been prepared in a manner as hereinafter described; and means whereby the said drawing paper or the like may be expeditiously released therefrom.

10 In general the invention takes the form of two precisely similar attachments situated along the top and bottom edges of the drawing board or the like each of which consists of:—

I. A thin metal bar extending approximately 15 the entire length of the drawing board or other surface (hereinafter called the clamping bar) and having an inturned edge or lip whereby, under the influence of spring pressure the drawing or writing material is secured to said surface.

20 II. Means whereby the said clamping bar may be raised by cam action against the said spring pressure for the purpose of releasing the said drawing or writing material.

25 Since by the invention the use of drawing pins is entirely obviated, the surface on which the material is to be affixed is prepared as herein-after explained for the reception and retention of the said material.

30 A particular arrangement and application of the device is illustrated in and fully described by reference to the accompanying drawing;

35 Figures 1, 2, and 3 show respectively a side elevation, a plan and an end elevation of a portion of the bottom edge of a drawing board fitted with the attachment which is the subject of this invention.

The clamping bar A may be formed to the section 40 shown from steel plate by rolling or drawing and may be covered with leather cloth or otherwise as a suitable finish.

45 Symmetrically and perpendicularly to the length of the bar A are attached leaf springs such as B which, in turn, are secured to the underside of the drawing board D by the screws C.

50 Mounted within the bar A is a bar E (hereinafter called the cam bar) of rectangular section and preferably of brass. This is arranged to slide longitudinally, being provided with two knobs such as F, situated near the ends of bar A, which operate in slots such as G cut therein.

55 Situated perpendicularly to the edge and symmetrically to the length of the drawing board are mounted three or more pins such as H. These project into corresponding inclined slots J

cut in the cam bar E so that when the latter is moved downwards (Fig. 1) by the knob F the clamping bar A is raised to the position shown dotted in Fig. 3 thus releasing the drawing or writing material. The length of E is equal to that of A less the projected length of slots J which thus governs that of slots G.

In order that, when in use, the lip of the clamping bar A may not foul the T square or set-squares, the top and bottom edges of the drawing board may be chamfered as shown at K Fig. 3.

The top or the bottom of the drawing board is also provided with a longitudinal saw-cut L to accommodate the inturned edge of the drawing pad or packing sheet M which may be plain or may have printed on it any system of graph lines so that when using semi-transparent drawing or writing materials, scales may be dispensed with for certain classes of work.

As shown in Fig. 1 some or all of the inclined 20 slots in the said cam bar may be arranged to depress the said clamping bar as well as raise it, thus providing means of applying a somewhat greater pressure on the material being clamped than the said springs can exert, when so desired. For example, the inclined slot engaging with the central pin or projection on the edge of the board may be arranged to only depress the clamping bar whilst the slots at the extremities 25 may be devised to merely raise it; suitable clearances in the cam bar above or below the slots being provided. Or again the cam bar may be in separate portions; one portion being arranged to raise the clamping bar, whilst others serve to 30 depress it.

35 For production on a large scale an alternative 40 method of construction, which however in no wise departs from the spirit and principle of the invention described, consists in making the cam bar E from drawn steel or brass and of a shallow channel or similar section; the inclined slots and cam faces for engagement with the said projecting pins or brackets being punched and pressed out where required.

45 I claim:—

1. A surface board, two opposite edges thereof 50 partially bevelled or chamfered, means for holding or retaining thereon drawing, writing or similar material, comprising clamping bars of suitable section and of a length approximately equal to the aforesaid surface board, means for mounting said clamping bars along the top and bottom vertical edges thereof, said mounting means consisting of a suitable number of like members fixed 55

- perpendicularly to said clamping bars and firmly attached to the under side of the aforesaid surface at points remote from the board edges, fixed 5 projections mounted on said edges, horizontally movable cam bars for raising and depressing said clamping bars relative to the board surface, said cam bars associated with and slidably mounted within the section of the clamping bars, and having inclined slots engaging with said fixed projections, upper edges on said clamping bars serving 10 to secure the said material with uniform pressure everywhere along the said partially bevelled or chamfered upper surfaces of the board edges.
- 15 2. A surface board, means for holding and stretching thereon drawing or writing material, the longest opposite vertical edges of the surface board being partially bevelled or chamfered at the uppermost corners thereof, metal clamping bars of channel section and of length approximately equal to said surface board, webs of clamping bars arranged approximately parallel to said vertical edges, springs fastened to lower flanges of clamping bars, extremities of said springs attached to under side of surface board, short pins or projections fixed to said vertical edges, bars sliding within the section of the clamping bars and having inclined slots engaging with said pins, whereby clamping bars may be raised or depressed, upper flanges on clamping bars serving 20 to secure drawing or writing material with uniform pressure everywhere along the upper bevelled surfaces of the board edges.

3. A surface board, means for stretching and retaining thereon drawing or writing material comprising clamping bars of hollow section and of length approximately equal to said surface board, two opposite partially bevelled edges on board contiguous with the surface thereof and parallel to said clamping bars, horizontally movable cam bars for raising and depressing said clamping bars relative to said bevelled edges, means for mounting said clamping bars along 10 said bevelled edges, said mounting means consisting of a suitable number of like members attached to the underside of the board and having their bending or hinging points situated below and remote from the upper edges of said clamping bars, upper edges of opposite clamping bars moving in curved paths away from each other when being depressed towards said bevelled edges and thereby clamping material in a taut manner over the board surface. 15

4. A surface board, means for securing drawing or writing material thereon, comprising cam-operated clamping bars and bevelled edges as claimed in claim 1, a detachable packing sheet or pad having one edge turned or formed approximately to a V-section for use with said material, means for mounting said packing sheet on surface board independently of said material consisting of a horizontal slit or sawcut beneath one bevelled edge of surface board to accommodate said 20 turned edge.

VIVIAN CHARLES ERIC MARTEN-
GWILLIAM.
